UNITED STATES PATENT OFFICE.

GRANVILLE T. WOODS, OF CINCINNATI, OHIO, ASSIGNOR TO THE WOODS
ELECTRIC COMPANY, OF SAME PLACE.

ELECTRO-MECHANICAL BRAKE.

SPECIFICATION forming part of Letters Patent No. 368,265, dated August 16, 1887.

Application filed November 3, 1886. Serial No. 217,860. (No. 1,111,111.)

To all whom it may concern:

Be it known to my concern:
Be it known that I, GRANVILLE T. Woods,
a citizen of the United States, residing at Cin-
cinnati, Ohio, have invented new and useful
Improvements in Electro-Mechanical Brakes,
of which the following is a specification.

My invention relates to braking apparatus for railway-cars, its object being to simplify and render the same more efficient and durable, with a view, primarily, to the use of the electric current as a means of controlling the power employed in braking.

To this end it consists in the construction and arrangement of mechanism and mode of applying and controlling the power used, as hereinafter more fully set forth.

Mechanism embodying my invention is illustrated in the accompanying drawings, in which—

20 Figure 1 is a side elevation of a portion of a car to which my invention is applied; Fig. 2, a plan view of the swinging frame with counter-shaft, friction-pulley, winding-drum, governor, and some of the connected parts; and

25 Fig. 3 an enlarged detail of the "governor."

Fig. 3 an enlarged detail of the "governor." Referring, now, to the drawings, A designates the car; B B, the truck-wheels; C, the bolster of the car-truck; *a*, the car-axle. In my invention I employ the rotative force of the car-
30 axle as the braking power; but have kept in view the desirability of allowing the braking apparatus to remain inert when not directly in use, in order to avoid the unnecessary wear of rotating parts. I have also adopted the
35 system of brakes normally acting except when held out of action by a superior force; and I therefore so arrange the mechanism that, except when temporarily held out of action, it acts to set the brakes whenever the cars are
40 in motion.

Pivoted to the bolster C (or to the car-body) is a frame, *c*, at the outer end of which is mounted a counter-shaft, *d*, driven by a friction-gear, *b*, rigidly attached upon it, when 45 brought by the pendulous movement of the frame *c* into rotatative contact with a friction-gear, *e*, rigidly secured upon the car-axle *a*. Adjacent to the friction-gear *b*, and loose upon the shaft *d*, is a winding-drum, *f*, upon which 50 winds a chain or belt, *g*, connecting with the ordinary brake-lever. (Not shown.) Next

beyond the drum f upon the shaft d is a friction plate or disk, h , having a "slot-and-feather" connection with the shaft. The plate h at one side and the hub b' (which may be enlarged into a disk of corresponding size) of wheel b at the other side of the drum f constitute the frictional clamping-surfaces between which the drum is held and rotated when in action. The plate h is normally held against the drum (and the latter against the opposite hub-surface) by a coiled spring, s , whose opposite abutment is the sliding collar i of an apparatus in the form of an ordinary steam-engine governor attached to the counter-shaft, 65 and constructed as follows:

The governor consists of two bell-crank arms, k , held pivotally at their elbow corners in a fixed collar, k' , upon the shaft, weights w , attached to the adjustable termini of the long arms, and links l , connecting the termini of the short arms with a sliding collar, i . Thus the action of the governor when in action, as will be seen, is to increase the force of the spring and hold the winding-drum f more firmly between surfaces, thus increasing the winding force upon the chain a . 75

The spring s should be of sufficient force (when unassisted by the governor) only to hold the brakes to the wheels with slight force, which force, as will be seen, will be increased by the speed of the car through the action of the governor. The governor apparatus has, however, a further function which justifies its name. In case the braking force should "skid" the wheels B , the rotation of the counter-shaft d would be arrested, and the action of the governor in such case would release the spring to its normal position and loosen the brakes sufficiently to allow the wheels to rotate by lessening the holding friction upon the drum f . The normal force of the spring s may be increased or diminished by shifting the terminal pin-connections of the governor-arms k with the links l upon the latter in the series of apertures provided, as shown in Fig. 3.

In the drawings I have shown the brake-chain g passed around idler-pulleys m m' and connected ultimately to the car-body and engaging the ultimate brake rod or chain g' by means of a suspended pulley, g^2 , in the bight of the chain g ; but this multiplication of pul-

leys may be omitted and the connection with g' made direct, if preferred and the general conditions admit.

It only remains to describe the electrical part of the apparatus. I employ the electric current for the purpose only of elevating the pivoted frame c to hold the friction-gears b and e out of contact. For this purpose any of the generators, conductors, and other preliminary apparatus may be employed, and as these are well known I have not thought it necessary to exhibit the same in the drawings. Assuming, then, that the same means of generating and controlling the current is provided, I employ on the car-body an electric motor, D , interposed in a multiple-arc ground-circuit, n n' , connecting the main electric conductor E to ground at one of the wheel-bearings. This current may, however, be interposed between an outgoing and a return conductor, or arranged in any suitable manner, according to the electrical system adopted, the object, as far as my invention is concerned, being merely to obtain the energizing force in the motor D in any convenient manner.

The shaft o of the motor is extended into or geared with a winding-drum, p , upon which winds a chain, r , passing over an idler-sheave, t , and forming a suspension-loop connected to the car-body, carrying a sheave, t' , connected with the frame c in the bight of the loop.

The arrangement and electrical connections are such that when the electric current energizes the motor its rotation winds up the chain r and holds the friction-gears b e out of contact, and the braking apparatus is inert. I also prefer to add an ordinary hand-wheel and shaft, F , with winding-chain u , connecting with the chain r , to operate the apparatus by hand when required—as, for example, when the car thus provided is attached to a train-uprovided with the electrical connections. The ordinary hand-brake connections may also be employed to connect directly with the brake-levers, as my apparatus does not in any way interfere with their use.

I claim as my invention and desire to secure by Letters Patent of the United States—

1. In combination with a railway-car and its truck, and a friction-gear carried upon one of its axles, a swinging frame pivoted to the bol-

ster and carrying a counter-shaft with a friction-gear, said frame adapted to swing its counter-shaft gear by gravity into engagement with the friction-gear upon the axle, a winding-drum upon the counter-shaft winding the brake-chain when driven by contact of the gears, and a motor and electric connections rotating a second winding-drum provided with a chain and pulleys for lifting the frame and holding the brake-gears out of contact when energized, substantially as set forth. 55

2. In electro-mechanical brake mechanism of the character described, in combination with and upon the counter-shaft carrying a friction-gear adapted to be alternately engaged with a similar gear upon the car-axle, a laterally-fixed friction disk or surface, a laterally-movable friction disk or surface, a loose winding-drum between and engaged by lateral contact of the two friction-surfaces, and a centrifugal governor attached to and rotating with the counter-shaft and controlling the movable friction disk or surface, substantially as and for the purpose set forth. 60

3. In electro-mechanical brake mechanism of the character described, in combination with the adjustable counter-shaft d and its friction-gear b , the fixed and adjustable friction disks or surfaces b' h , the interposed winding-drum f , the centrifugal governor, and the spring s , interposed between the sliding collar i of the governor and the adjustable friction-disk h , substantially as and for the purpose set forth. 70

4. In electro-mechanical brake mechanism of the character described, the combination, with and upon the driven counter-shaft, of the fixed friction disk or abutment b' , the loose winding-drum f , the movable friction-disk h , 85 the spring s of the governor as constructed, embodying the pivoted bell-crank arms k , weights w , extensible links l , and sliding collar i , substantially as and for the purpose set forth. 90

In testimony whereof I have hereunto set my hand in the presence of two subscribing witnesses.

GRANVILLE T. WOODS.
